United States Patent Office

Des. 201,336
Patented June 8, 1965

201,336

NURSING BOTTLE

Warren W. Nelson, 5132 Logan Ave. S.,
Minneapolis, Minn.

Filed Oct. 12, 1964, Ser. No. 82,137

Term of patent 14 years

(Cl. D83—8)

FIG. 1

FIG. 2

FIG. 3

FIG. 4

FIG. 1 is a view in perspective of a nursing bottle showing my new design, the side opposite that shown being a mirror image;

FIG. 2 is a view in side elevation thereof;

FIG. 3 is a view in end elevation thereof as seen from left to right of FIG. 1, and

FIG. 4 is a view in end elevation thereof as seen from right to left of FIG. 1.

I claim:

The ornamental design for a nursing bottle, as shown and described.
